UNITED STATES PATENT OFFICE.

CHARLES W. CHENEY, OF BOSTON, MASSACHUSETTS.

MASSAGE APPARATUS.

Application filed August 1, 1925. Serial No. 47,405.

This invention pertains to the art of therapeutic massage and more particularly to apparatus for the reduction of excessive weight by mechanically breaking down fatty tissue.

As usually performed the massage operation, whether accomplished directly by the hand of the operator, or indirectly by the use of manually or power actuated vibrators, is very fatiguing and cannot effectively be performed by the patient himself. The patient is thus dependent upon the employment of a skilled operator and the annoyance incident to keeping definite appointments for treatment as well as the high price usually charged for such treatments often deters patients from taking such a course of treatment or induces them to discontinue such a course too soon.

In accordance with my present invention I have devised a massage apparatus which, while useful as an adjunct to the equipment of the professional masseur, is particularly useful in the self-treatment of the patient since it enables the patient with but slight effort on his own part to obtain results in flesh reduction which so far as is known to me are attainable otherwise only by subjecting the patient to a long and expensive course of treatment at the hands of a skilled operator.

In the accompanying drawings I have illustrated by way of example a preferred embodiment of the present invention and in the drawings,

Fig. 1 is a side elevation of a massage apparatus constructed in accordance with the present invention;

Fig. 2 is an elevation of the left hand side of said apparatus as viewed in Fig. 1; and

Fig. 3 is a fragmentary vertical section to larger scale illustrating a preferred form of applicator constituting an element of the apparatus.

Referring to the drawings the numeral 1 designates a suitable platform or base upon which the operator may stand during the treatment. Substantially vertical posts 2 are disposed at the corners of this base, which is conveniently rectangular. These posts are connected at their upper ends by horizontal cross rails 3 thus forming a substantially rectangular rigid frame of a

height somewhat greater than that of the tallest patient. The top of this frame may be open or closed as may be desired.

Near one side of the frame, and in the plane of such side if desired, or spaced therefrom as here shown, a pair of parallel spaced vertical guide members 4 and 5 are disposed with their upper ends engaging a cross rail 45. These guide members are secured at their lower ends to the base 1 and at their upper ends to the cross rails 3. These vertical guides 4 and 5 define a predetermined fixed path along which a carriage 6 may be moved.

The carriage 6 preferably comprises spaced horizontal members 7 and 8 having openings at their opposite ends for the reception of the guide bars 4 and 5 respectively. Preferably a chain or cord 11 attached at one end to the upper part of the carriage 6 passes up over a sprocket wheel or pulley 12 and has a counterbalance weight 16 secured to its other end. This sprocket wheel or pulley 12 is fixed to a horizontal shaft 13 turning in bearings 14 and 15 carried by the guides 4 and 5.

The shaft 13 is provided at one end with a worm wheel 17 which meshes with a worm 18 of low pitch carried by a shaft 18^a turning in a bearing 19 supported by a bracket 19^a mounted on one of the posts 2. The shaft 18^a is furnished with a hand wheel 20 conveniently located to permit the operator to turn the shaft 18^a and thereby raise or lower the carriage to the desired level. The carriage supports a motor 21, preferably an electric motor having a flexible conductor, not shown, leading to a suitable source of electrical energy. The carriage also supports a horizontal applicator shaft 22 mounted in suitable bearings in the front and rear members 22 and 23 respectively of the carriage and having its inner or forward end projecting forwardly from the front member 24 of the carriage. A suitable speed reducing gear train transmits movement from the motor shaft to the shaft 22.

The carriage 6 is preferably provided with a front guard plate 25 and a top guard plate 26 which conceal the carriage proper and shield the patient from contact with the motor and the gear train.

An applicator A is detachably secured to

that end of shaft 22 which projects forwardly beyond the guard 25.

This applicator, for effective use in flesh reduction, should be of that type which comprises a head carrying a plurality of hard polished knobs which are adapted to produce deep indentations in the flesh of the patient and rapidly to advance such indentations, with the intervening wrinkles or ridges, as the applicator head is rotated.

The specific arrangement shown in Fig. 3 employs a head consisting of a base plate or disk 27 fixedly secured to the shaft 22, and a cover plate 28 spaced from the base 27 by means of suitable spacer posts 29. The base disk 27 and the cover disk 28 are furnished with a plurality of coaxial openings preferably symmetrically arranged with reference to the axis of the head. Each opening in the base 27 is screw threaded for the reception of a threaded stud 30 projecting from the rear end of a cylindrical sleeve member 31 whose forward end projects through the corresponding opening in the cover disk 28. The opening in the latter disk is larger than the opening in the base 27 and is adapted to receive a second sleeve member 32 telescoping over the sleeve 31. The sleeve member 32 is closed at its outer or forward end 33, such end being smoothly rounded and preferably polished. The rear or inner end of the sleeve 32 is furnished with a radial flange 34 or equivalent stop member element, adapted to engage the rear surface of the cover 28 and thus to form a stop to limit the outward movement of the sleeve 32. A coiled compression spring is seated within the sleeve 31 and bears against the inner surface of the head 33 of sleeve 32, thus tending to force the sleeve 32 forwardly into the position indicated in Fig. 3 but permitting the sleeve to recede when subjected to sufficient pressure. The sleeve 32 is preferably of some hard rigid material such for example as nickel steel.

The upper members 33 of the frame form convenient means for suspending curtains 36 or other suitable closure means adapted to enclose the space within the frame and to form a cabinet within which a patient may stand while taking the treatment.

In the operation of the device the patient stands upon the platform 1 and adjusts the carriage by means of the hand wheel 20 until the applicator A is at the proper height to engage that portion of the patient's person which is to receive the treatment. Since the carriage is counterbalanced, this adjustment is easily made and by employing the worm and wheel adjustment or equivalent means the carriage is positively held in any position to which it may be adjusted.

The motor is now started and the patient leans toward the applicator, thus pressing the body against the latter with as much pres-

sure as may be desired. To obtain greater pressure the patient may grasp the uprights of the frame, thus exerting the muscular force of the arms to press his body against the applicator.

The rapid rotation of the applicator produces, as above described, alternating depressions and ridges in the flesh which are rapidly advanced with reference to the surface of the body as the applicator rotates and this action, which is accompanied by very substantial skin friction is found highly effective for the desired purpose of reducing excessive flesh. By employing an applicator having hard polished knobs mounted to yield relatively to the head, all danger of injury to the patient is avoided while a uniform and very effective action is secured.

Since the carriage with the applicator is adjustable to any desired height the applicator may be applied to any part of the patient's body including both trunk and limbs and obviously applicators of different sizes and having knobs of different shapes may be attached to the shaft 22 in accordance with the needs of the patient and the part of the body to be treated. Moreover, since the pressure of the applicator against the patient's body is always controlled by the patient there is no danger of overtreatment and injury to the patient.

While I have illustrated a preferred embodiment of the invention I wish it to be understood that the invention is not necessarily limited to the details of construction herein disclosed but that equivalent elements may be substituted for those herein described and that variations in shape, relative arrangement and proportions of parts and in the materials employed may be made as circumstances may warrant without departing from the spirit of the invention.

I claim:

1. Massage apparatus comprising a vertical guide, a carriage sliding along the guide, a worm and wheel for adjusting the carriage along its guide and for retaining it in adjusted position, a motor mounted on the carriage, a horizontal shaft journaled in the carriage and projecting from one side thereof, an applicator mounted upon the projecting end of the shaft, and a train of speed reducing gears connecting the motor to the shaft.

2. Apparatus of the class described comprising a frame having uprights connected at top and bottom to provide a rigid structure, a carriage mounted to slide in a predetermined path at one side of the frame, means for adjusting the carriage along said path and for positively holding it in adjusted position, a motor mounted on the carriage, an applicator shaft journaled in the carriage, a train of gears transmitting mo-

tion from the motor to the applicator shaft, the carriage having a shield at its inner side concealing the motor and gear train, said shield having an aperture for the end of 5 the applicator shaft to project through, and an applicator mounted upon the projecting end of the shaft outside of said shield and

adapted to sustain the pressure of the body of a person positioned within the frame and pressing against the applicator.

Signed by me at Boston, Massachusetts this 30th day of July 1925.

10
